UNITED STATES PATENT OFFICE

MARCUS B. WHITNEY, OF DARIEN, CONNECTICUT

PAD

Application filed October 2, 1930. Serial No. 485,988.

This invention relates generally to the class of stationery, and has particular reference to an improved pad which, while not necessarily restricted to such use, is especially designed 5 as a combined calendar and appointment or memorandum pad.

Broadly, the invention comprehends a pad which includes a plurality of sets of leaves differing in numbers and sizes and having a 10 common binding by which the leaves are secured in superposed relationship in successively deeper groups, the leaves of each group bearing related matter which runs serially from the top of each group to the bottom of 15 the widest group, the mode of securing the leaves being such as to permit of the simultaneous display of the related matter.

The invention further aims to provide a 20 pad having groups of leaves so arranged that the tearing off of the leaves does not destroy the relation of the grouping arrangement.

The invention furthermore resides in a pad of the indicated character which is comparatively simple in its construction, inexpensive 25 to produce and which is highly efficient in its purpose.

With the above recited and other objects in view, reference is had to the following description and accompanying drawings, in 30 which there is exhibited one example or embodiment of the invention, while the claims define the actual scope of the same.

In the drawings:

Figure 1 is a perspective view of a calendar pad constructed in accordance with the invention.

Figure 2 is a plan view of one of the lowermost group of leaves.

Figure 3 is a plan view of one of the intermediate group of leaves.

Figure 4 is a plan view of one of the upper group of leaves.

Referring to the drawings by characters of reference, A designates a backing or base upon which a plurality of successively more numerous and narrower sets of leaves B are arranged in superposition, and to which base and each other the leaves are bound by a common binding C. In its principal use as a cal-

endar, the leaves B are divided into and comprise three successively deeper groups 1, 2 and 3, the group 1, consisting of the widest set, corresponding in number to the number of months in the year, the group 2, consisting of 55 the combined widest and next widest sets, corresponding in number to the number of weeks in a year, and the group 3, consisting of all three sets, corresponding in number to the number of days in a given year. The group 1 is of greater size than the remaining groups, either in one dimension as illustrated or in several or all dimensions, so that the group 1 has a portion a which extends beyond the area or confines of the remaining groups and 60 has inscribed thereon indicia b respectively identifying the months of a given year. The group 2, while of lesser size than group 1, is of greater size than group 3, providing on each sheet of group 2 an extending portion c 65 which is provided with indicia d identifying the weeks of a given year. The group 1 is also provided with portions e which underlie the extending portions c of the group 2 and which correspondingly respectively bear 70 identifying indicia d for the weeks of the given year. The remaining leaves constituting group 3, together with the portions f and g which directly underlie group 3, are respectively inscribed with indicia h identifying 75 the days of a given year. In each instance the indicia has serial continuity from the top of each group to the bottom of the widest group and occurs as follows: The indicia b (Fig. 1) consists of the names of the months 80 and number of a given year, therefore reading "January 1930" on the portion a and "December 1930" on the bottom leaf (Fig. 2). The indicia d in group 2 begins with "Week ending January 4, 1930" on the top 85 portion c and extends not only through the leaves of the instant set but continues throughout the group 2 which includes the portions e so that the medial portion of the bottom page reads "Week ending January 3, 90 1931" (Fig. 2). The indicia h begins with "Wednesday, January 1, 1930" and continues through the entire group 3, embracing the portions f and g of the groups 2, 1, so that the bottom portion reads "Wednesday, Decem- 95 100

ber 31, 1930" (Fig. 2). In practice, the sheets of group 2 may be made of a better quality or heavier grade of paper than the sheets of group 3, while the sheets of group 1 may be made of a still better quality or still heavier paper than the sheets of group 2, for the reason that the sheets of groups 1 and 2 remain in use longer than the sheets of group 3, and the sheets of group 1 remain in use longer than the sheets of group 2. In order to facilitate the separation and tearing off of the portions *a* of the sheets of group 1, the said portions *a* are joined to the remainder of the sheets by perforated lines *i*. The portions *c* of the sheets of group 2 are similarly joined to the remainder of said sheets by a perforated line *j* to facilitate the tearing off of said portions. The portions *e* of the sheets of group 1 are joined to the portions *g* thereof by a perforated line *k* to facilitate the tearing off of said portions *e*.

From the foregoing, it will thus be seen that an improved pad has been designed, especially for use as a calendar, and while there has been illustrated a single and preferred embodiment of the invention, it is to be clearly understood that no limitation is necessarily made to the precise structural details herein exhibited, but that variations and modifications which properly fall within the scope of the claims may be resorted to when desired.

What is claimed is:

1. A calendar pad including a plurality of superimposed bound leaves corresponding in number to the number of days in a given year; a lower group of said leaves corresponding in number to the number of months in a year and being of greater size than the remaining leaves and bearing respectively on the portions thereof which extend beyond the remaining leaves, indicia identifying the months of the year; an intermediate group of leaves which combined with the lower group of leaves equals the number of weeks in the year, said intermediate group of leaves being of greater size than and having a portion extending beyond the remaining upper group of leaves, the extending portions of said intermediate group of leaves and the portions of the lower group of leaves which underlie said extending portions of the intermediate group of leaves bearing respectively thereon indicia identifying the weeks of the given year; and the remaining upper group of leaves and the portions of the intermediate and lower group of leaves which underlie the uppermost group of leaves bearing respectively thereon indicia identifying the days of the given year.

2. A calendar pad including a plurality of superimposed bound leaves corresponding in number to the number of days in a given year; a lower group of said leaves corresponding in number to the number of months

in a year and being of greater size than the remaining leaves and bearing respectively on the portions thereof which extend beyond the remaining leaves, indicia identifying the months of the year; an intermediate group of leaves which combined with the lower group of leaves equals the number of weeks in the year, said intermediate group of leaves being of greater size than and having a portion extending beyond the remaining upper group of leaves, the extending portions of said intermediate group of leaves and the portions of the lower group of leaves which underlie said extending portions of the intermediate group of leaves bearing respectively thereon indicia identifying the weeks of the given year; the remaining upper group of leaves and the portions of the intermediate and lower group of leaves which underlie the uppermost group of leaves bearing respectively thereon indicia identifying the days of the given years; the portion of the lowermost group of leaves bearing the month identifying indicia being joined by a weakened line to the remaining portion thereof; and the portions of the intermediate group of leaves bearing the week identifying indicia being joined by a weakened line to the remaining portion thereof.

3. A calendar pad comprising a plurality of superimposed bound leaves including a lower group corresponding to the number of weeks in a year and an upper group which combined with the lower group corresponds to the number of days in a year, the lower group being of greater size than the upper group and having respectively on the exposed portions of the leaves week indicating indicia and on the concealed portions thereof day indicating indicia and the upper group having respectively on its individual leaves day indicating indicia.

4. A calendar pad comprising a plurality of superimposed bound leaves including a lower group corresponding to the number of months in a year, an upper group which combined with the lower group corresponds to the number of days in a year, the lower group being of greater size than the upper group and having respectively on the exposed portions of its leaves month indicating indicia and on the concealed portions of the leaves day indicating indicia and the upper group having respectively on its individual leaves day indicating indicia.

5. A calendar pad comprising a plurality of sets of successively more numerous and narrower leaves superposed upon each other to provide successively deeper groups, the leaves of each of the groups bearing indicia having serial continuity from the top of each group to the bottom of the widest group, and a common binding for the leaves.

MARCUS B. WHITNEY.
